UNITED STATES PATENT OFFICE.

WILLIAM WALTER SWHIER, OF PORTLAND, INDIANA.

CONCRETE-FINISHING MACHINE.

Application filed May 22, 1923. Serial No. 640,790.

To all whom it may concern:

Be it known that I, WILLIAM WALTER SWHIER, a citizen of the United States, residing in the city of Portland, in the county 5 of Jay, State of Indiana, have invented a new and useful Concrete-Finishing Machine, of which the following is a full, clear, and comprehensive specification and exposition, being such as will enable others to 10 make and use the same with exactitude.

The object of my present invention, broadly speaking, is to provide a concrete finishing machine which is comparatively simple in character, strong and durable in construction, positive in its results, easily operated and controlled, automatic in its several actions, and which can be manufactured and sold at a comparatively low price.

More specifically stated, my object is to 20 provide a finishing machine especially adapted for concrete roadways, the same being adapted to be driven by power carried thereby and arranged to automatically accomplish three distinct operations or results at one time, namely: Striking off, tamping, and belting, whereby when the concrete compost is delivered in front of the machine the machine completely finishes the roadway without the employment of 30 manual labor applied thereto.

Other minor objects and particular advantages of the invention will suggest themselves in the course of the following description, when taken in connection with the accompanying drawings, and that which is new will be correlated in the appended claims.

The preferred means for carrying out the principles of my invention in a practical 40 manner is shown in the accompanying drawings in which—Figure 1 is a top plan view of the entire machine. Figure 2 is a front elevation of the same. Figure 3 is a right-hand end elevation of the same. Figure 4 is a rear elevation of the same. Figure 5 is a 45 left-hand elevation of the same. And Figures 6 and 7 are detail views of the guide-arm for the means by which the belting-strip is carried.

Similar indices denote like parts throughout the several views.

In order that the construction, the operation, and the several advantages of the invention may be more fully understood and 55 appreciated I will now take up a detailed description of the same, in which I will set

forth the various features thereof as fully and as comprehensively as I may.

The framework of my construction comprises the front sill 1, the rear sill 2, and 60 the right and left end sills 3 and 4, respectively, all of which are rigidly connected at their ends forming a parallelogram-shaped frame, which is retained in shape by the braces 5 and 6 rigidly secured thereto as 65 shown.

The central portion of the base frame just mentioned is supported by two arched bents 7 and 8, which are secured at their ends to the ends of the respective sills 1 and 2, extending thereover throughout their lengths. 70 The bent 7 is rigidly connected with the sill 1 by the vertical posts 9, 10, 11, 12 and 13. Likewise the bent 8 is connected with the sill 2 by the posts 14, 15, 16, 17 and 18. 75

Intermediate sills 19, 20 and 21 connect the sills 1 and 2.

Secured underneath each of the corners of the base frame above described is a hanger, as the hangers 22, 23, 24 and 25, in which 80 are revolvably mounted the respective carrying wheels 26, 27, 28 and 29, which are adapted to roll forward and rearward to carry the device. The wheels 28 and 29 are connected by the shaft 30, the central portion of which operates in the hanger 31 which extends down from the sill 2 to carry 85 said shaft.

The power plant comprises a conventional motor 32, which has a shaft 33 by which 90 power is delivered from the motor to operate the parts of the machine.

A bevel pinion 34 is secured on the projecting end of the shaft 33, for the purpose herein set forth. 95

Cross bars 35 and 36 are secured to the sills 19 and 20, the former being near the center and the latter near the forward side of the machine. Carried by said cross bars, and extending upward therefrom, are the 100 respective pedestal bearings 37 and 38, which carry the revolvable shaft 39. The rear end of said shaft carries the bevel gear 40, which meshes with the pinion 34. And near the gear 40 the shaft 39 is further supported 105 by the bearing 41 which extends up from the bar 42, which in turn is carried by the sills 19 and 20. Secured on the shaft 39, between the bearings 37 and 38, is a worm-gear 43, for the purpose hereinafter explained. 110

The shaft 44 lies at right-angles to and on

- a lower plane with relation to the shaft 39. The shaft 44 is carried by the bearings 45, 46 and 47, which extend up from the respective members 19, 20 and 21. The shaft 5 44 is adapted to be rotated by means of a worm gear pinion 48 secured thereon and meshing with the worm gear 43. Mounted slidably endwise on the shaft 44 but revolvable therewith, is the elongated collar 49. 10 Secured on one end of said collar is the large bevel gear wheel 50, which faces to the left, and secured on the other end of said collar is the bevel pinion 51, which faces to the right. 15 Extending between and carried by the sills 20 and 21 are the two cross-bars 52 and 53, the former being near the center and the latter being near the rear sill 2. A bearing 54 is mounted on top of the bar 52, and in 20 alignment therewith. A bearing 55 is secured to the underside of the bar 53 (shown in Fig. 4) where it is secured by bolts 56. A shaft 57 is carried by the bearings 54 and 55 and it, of course, extends at an angle, 25 extending downward from its forward end to the lower end, which latter is a short distance above the shaft 30, while its forward end is in alignment with the shaft 44. On 30 the forward or upper end of the shaft 57 is secured the bevel gears 58 and 59, the former being adapted to mesh with the pinion 51, and the latter with the wheel 50, that is when the collar 49 is shifted to the right or the left, respectively. 35 The face of the wheel 50 is hollowed out, inward from the gear teeth thereof, whereby the gear teeth of the gear 58 may enter therein without engagement therewith during the time the wheel 50 and the gear 59 40 are in engagement with each other. The back of the wheel 50 carries a channeled projection 60 concentric thereof, in which operates the forked spanner lever 61. A block 62 rests on the bar 52 and it has three 45 notches, *a*, *b* and *c*, in its face, in either of which may rest the handle portion of the lever 61. Said lever is the means by which the collar 49 may be shifted endwise as desired, however I am not to be limited to 50 this means, as various other means may be provided for said shifting. The lower or rear end of the shaft 57 carries a worm-gear 63 which meshes with the worm-pinion 64, which latter is secured 55 on the shaft 30. When the lever 61 is in notch *b* the device will be in neutral, that is the machine will be stationary. Should now the lever be 60 slightly lifted and then shifted into notch *a* then the collar 49 will be carried to the right and the pinion 51 will be brought into mesh with gear 58, thereby placing the machine in forward gear, for if the motor 65 be in operation the shaft 30 will be revolved to rotate the wheels 28 and 29 forwardly, thereby driving the entire machine forward. Now should the lever 61 be shifted into notch *c*, then the pinion 51 will be out of mesh with gear 58, and at this time the wheel 50 will be brought into mesh with the gear 59, therefore the machine will be caused to travel rearwardly, and at a speed faster than when it traveled forwardly. Secured on the shaft 44, near the bearing 45, is a bevel gear 65. Extending upward 75 from the cross-bar 36 is a bearing 66, and a similar bearing 67 extends upward from the sill 1. Said bearings 66 and 67 carry the shaft 68, on the rear end of which is secured the bevel gear wheel 69 which 80 meshes with the bevel gear 65. On the forward portion of the shaft 68 is the pinion 70, which meshes with the larger gear wheel 71, the latter being secured on the shaft 22 which is carried by bearings secured to the sills 1 and 2, as indicated only in dotted lines in Fig. 1. The ends of the shaft 72 have discs 73 and 74 secured thereon, and each of said discs carries a wrist-pin 75 and 85 76, respectively, which are eccentrically mounted with relation thereto and extend out therefrom. Said wrist-pins are offset 90 with relation to each other whereby when the shaft 72 revolves one of said pins will be in advance of the other. 95 Numeral 77 denotes the strike-off blade, which stands edgewise across the front of the machine and it extends the full length thereof, with its ends curved slightly forward. Said blade is supported as follows: 100 A rotatable rod 78 is carried by the bearings 79 and 80 which are secured to the upper portions of the posts 10 and 12, respectively, and the ends of said rod are turned forward at right angles thereto, and they terminate in the socket bearings 81 and 82, respectively. Numerals 83 and 84 denote suspension rods whose upper ends are universally mounted in the respective 105 bearings 81 and 82, with their lower ends pivoted to the blade 77 by the respective bolts 85 and 86. Rigidly secured to and extending down from the central portion of the rod 78 is the arm 87, and pivoted to the lower end of said arm, and extending rearward, is the lever 88 whose rear end terminates in an upwardly extending handhold, as shown in Fig. 3. A finger 89 extends to the right from the sill 20, on which the rear portion of said lever may rest, there being notches formed in the under 110 edge of the lever 88 to engage said finger when the lever is released. Therefore the blade 77 is suspended from the rod 78, and the blade may be raised and lowered as desired by the operation of the lever 88 forward or rearward, and the blade may be suspended at the height desired by engaging the lever with said finger 89. 115 The blade 77 is provided with push-arms 120 125 130

90 and 91, the forward ends of which are forked to provide an upper and a lower finger, and they are pivoted to swing laterally by means of the bearings 92 and 93. 5 respectively, which bearings are rigidly secured to the back of the blade 77. The rear ends of said arms 90 and 91 are mounted to the under sides of the cross sills 19 and 21, respectively, each by a compound, 10 double, or universal bearing, 94 and 95, respectively. Said arms afford great strength to positively push the blade forward, but at the same time permitting the blade to have lateral movements, which movements 15 are attained as follows: A pivot 96 extends back from the rear of the blade 77, and a link 97 extends between and is mounted on the pivot 96 and the wrist-pin 75, as in Fig. 2, whereby the rotation of the shaft 68 will cause the blade 77 to move alternately to the right and the left.

I will next describe the tamping mechanism: Numeral 98 denotes the tamping-bar, which is disposed underneath and extends almost the full length of the machine from right to left. Secured to and extending upward from the bar 98 are two guide-pins 99 and 100, which are adapted to slide up and down through apertures therefor in the respective guide-blocks 101 and 102. Said guide-blocks are carried by the respective cross-bars 35 and 52, from which it is apparent that the bar 98 has only vertical movements with relation to the machine, but of course it has a forward movement as it is carried along with the machine.

Extending upward from the sills 19 and 21 are the pedestal bearings 103 and 104, respectively. Extending between and rotatably mounted in said bearings is the shifting-shaft 105, which is adapted to be slightly turned by means of the handle 106 secured thereto. A smaller shaft 107 extends longitudinally of and through the shaft 105 but it is located eccentrically thereof as shown in Fig. 3, and it is adapted to revolve independently of the shaft 105. Pitman-heads 108 and 109 are mounted on the shaft 107 and adjoining the outer sides of the bearings 103 and 104, respectively.

Secured to and extending down from the respective heads 108 and 109 are the pitmans 110 and 111, whose lower ends are hinged to the bar 98. Secured on the projecting left end of the shaft 107 adjoining the pitman-head 109, is the gear wheel 112, which is adapted to mesh with the larger gear wheel 113, which latter is secured on the left end of the shaft 44.

It will now be seen that the revolving of the shaft 44 will result in revolving the shaft 107, thereby causing the pitmans to alternately move up and down, thereby im-

parting up and down movements to the tamping-bar 98.

The belting mechanism comprises a rod 114, extending the length of the machine, on the rear side thereof, and its end portions extend downward and then directly rearward forming the fingers 115 and 116, for the purpose hereinafter stated. Said rod 114 is mounted to slide endwise and rotatably in the bearings 117, 118 and 119.

Numeral 120 denotes a non-rotatable bearing through which the rod 114 extends, the rod 114 being provided with a projecting pin 121 which may move in the slot 122 formed through the bearing 120, as in Fig. 1, whereby the rod 114 and the bearing 120 must always move endwise together, yet permitting the said rod to have a limited rotary movement independent of the bearing 120, which movement is limited by the length of the slot 122.

Rigidly connected to the bearing 120 is a guide or bearing arm 123, which first extends directly forward from said bearing and then extends upward and rearward at an angle to near the underside of the sill 2 where it again extends directly forward in contact with the underside of said sill, this last forward portion being adapted to slide laterally in a slip 124 carried by the underside of the sill 2.

Numeral 125 denotes a pitman, one end of which is mounted on the wrist-pin 76, and its other end being mounted on the lower horizontal portion of the member 123.

By this arrangement it will be seen that as the shaft 72 revolves it will, by means of the pitman 125, cause the rod 114 to slide endwise, alternately to the right and the left.

Extending between and secured at its ends to the fingers 115 and 116 is the canvas or belting strip 126.

Attention is called to the fact that the bearings 22, 23, 24 and 25 are adjustable laterally, that is they may be moved inward from that shown, as the bolts by which they are secured may be changed to other holes formed in the sills, thereby adapting the machine to operate in making roadways of various widths.

The wheels 26, 27, 28 and 29 are adapted to travel on tracks A and B placed on each side of the proposed roadway and which are the same as ordinarily used to form the side edges of the roadway and by which the roadway is leveled or finished to grade.

In practice the proposed roadway is excavated to the desired depth, and the side rails A, and B, are located so that their upper edges will be at the grade line to which the roadway is to be made. My machine is then mounted on said rails, as shown, and with the motor running, then the operation will be substantially as follows: The concrete mixing machine first travels forward

between the rails A and B and delivers the desired amount of cemant compost between said rails. The lever 61 may now be shifted to notch *a* which will, as explained, cause the machine to travel forward, but quite slowly, whereby the previously deposited compost will first be engaged by the blade 77, which not only moves forward with the machine but it will have an endwise movement alternating to the right and the left, and in addition thereto it will have a third movement: First one end and then the other end moving in advance. The height of the blade 77 may be changed as desired by means of 50 15 the lever 88, and maintained in its adjusted position as heretofore described. The blade 77 will distribute the compost and will strike-off to the desired height as will be apparent.

Following the blade 77 will be the tamping-bar 98, which moves up and down and tamps the compost as desired; from the above it is apparent that the tamper has a forward movement and an up and down movement, and it may have a third movement if the eccentric mounting be changed to slightly advance one with relation to the other, thereby causing one end of the tamper to strike first. The tamper may be placed 55 25 out of gear by moving the handle 106 rearward, thereby turning the shaft 105 and moving the gear 112 out of mesh with the gear 113.

After the tamper has done its work and 35 passed on, it is followed by the belter or smoother strip 126, which moves endwise right and left upon the substantially level compost, and by the action thereof the surface is finished to the proper degree of 40 smoothness.

The strip 126 may be raised or lowered as desired by means of the bar 127 whose rear end is pivotally connected to the upper end of the arm 128 which extends up 45 from the rod 114, to which it is rigidly se-

cured. To retain the said strip at the height desired the forward downwardly turned end portion of the bar 127 may be inserted on one of the holes 129 where it will remain by gravity.

50

I desire that it be understood that various changes may be made in the several details of construction herein shown and described without departing from the spirit of the invention and without sacrificing any of the 55 advantages thereof which are new and useful and which involves invention.

55

Having now fully shown and described my invention, what I claim, and desire to secure by Letters Patent of the United States, is: 60

1. In a machine for finishing concrete roadways comprising in combination with a frame and a motor mounted on the frame, a strike-off blade carried by the frame, means for imparting alternate forward movements 65 to the ends of the blade, and means for simultaneous bodily movement thereof longitudinally of the blade in addition to the regular forward movement of the frame, and means for connecting said blade whereby said movement will be maintained by the 70 operation of said motor.

70

2. In a finishing machine for concrete roadways, a supporting frame, a strike-off device extending transversely of the frame 75 and mounted to permit bodily reciprocation transversely of said frame and alternate advancement of its respective ends, a motor on the frame, an operating connection between motor and strike-off device and clutch means 80 for connecting the last means to the operating connection whereby the strike-off device may be bodily reciprocated with advancement of its ends to effect the bodily reciprocation, means actuated from the motor for imparting intermittent forward movement to the alternate end portions of the strike-off device. 85

WILLIAM WALTER SWHIER.
